UNITED STATES PATENT OFFICE.

MANUEL BLICKMAN, OF NEW YORK, N. Y., ASSIGNOR TO SOPHIA BLICKMAN, OF BROOKLYN, NEW YORK.

DESIGN FOR A PEDESTAL.

58,060.

Specification for Design.

Patented June 7, 1921.

Application filed June 4, 1920. Serial No. 386,602. Term of patent 14 years.

To all whom it may concern:

Be it known that I, MANUEL BLICKMAN, a citizen of the United States, and resident of New York city, N. Y., have invented a new, original, and ornamental Design for Pedestals, shown in the accompanying drawing, forming a part of this specification, wherein—

Fig. 2 is a top plan view thereof.

What I claim is—

The ornamental design for a pedestal as shown.

MANUEL BLICKMAN.
